UNITED STATES PATENT OFFICE.

RAYMOND MOWER CONNER, OF PORTLAND, OREGON, ASSIGNOR TO PORTLAND GAS & COKE COMPANY, OF PORTLAND, OREGON, A CORPORATION OF OREGON.

PORTRABLE BAKE OVEN.

Application filed March 22, 1924. Serial No. 701,063.

This invention relates to portable bake ovens and it comprises a heat insulated chamber, a tile hearth within said chamber, a sheet metal top for said hearth, a gas burner 5 below the hearth, vertical passages for products of combustion between the sides of the hearth and the side walls of the chamber, a chimney at the rear of the chamber, a longitudinal flue extending across the top of the 10 hearth open at the front end and connected to the chimney at its rear end and a door located in the front wall of the chamber; all as more fully hereinafter set forth and as claimed.

In gas fired ovens of the type to which the 15 present invention relates the provision of an oven of a construction which permits of portability and which contains sufficient volume of refractory material for ample heat storage is a desideratum. It is very difficult in gas 20 fired ovens to obtain uniform distribution of heat and at the same time economically utilize the heat delivered by the gas burner. These difficulties are overcome in my oven by the unique and efficient construction to be 25 described.

One of the objects of this invention is the provision of a directly heated gas oven in which the products of combustion cannot come in contact with the material being 30 baked.

Another of the objects of this invention is the provision of an oven of the type described which is readily portable and which, at the same time, permits the combination of 35 two different heating systems.

One known type of oven is that in which the hearth heat is taken advantage of to give a slow but constant baking. Another known type of oven is that in which top heat is almost entirely relied upon to give intense 40 localized heat affording quick baking.

In the present invention the advantages of these types are attained by constructing the hearth of refractory tile or brick which heats 45 slowly and retains its heat for a long period of time, and by providing the hearth with a metal top which transmits the heat readily and permits rapid heating of the interior of the hearth while the tiles are still comparatively cool.

In the accompanying drawing I have shown one form of a specific embodiment of my invention.

Figure 1 is a vertical section through an 55 oven on line 1-1 of Figure 2;

Figure 2 is a horizontal section on line 2-2 of Figure 1.

Referring to the drawings numeral 1 indicates the hollow walls of the oven, usually constructed of sheet metal or the like. These 60 walls are filled with heat insulating material 2 and are fastened together by angle bars 3 and rivets 4. Located in the front wall of the oven is door 5 provided with suitable 65 hinges 6 to permit ready opening thereof. Built within the oven is a hearth designated as a whole by 7 and comprising bottom tile 8, side tile 9 and top 10 preferably of sheet 70 metal or other material which readily conducts heat. Located beneath the hearth 7 is gas burner 11. Between the side walls of the 75 oven and the hearth 7 are provided vertical passages 12 for the products of combustion from the gas burner. Extending along the top plate 10 is flue 13 open at its front end 14 and extending through the rear wall of the oven, being attached at its rear end to vertical chimney 15. Vertical legs 16 or the like are attached to the corners of the oven.

A sheet metal box 17, opened at the top, 80 is provided for carrying and supporting the gas burner 11. This box extends through the front and rear walls of the oven and supplies air for combustion of the gas.

In operations, the oven may be used for 85 rapid baking by reliance on the top heat; or it may be used for baking hearth bread or the like, relying upon the heat stored in the hearth alone; or the baker may obtain any desired proportion of top and bottom heat. 90

If it is desired to bake rapidly, relying on top heat alone, the material to be baked is placed on the hearth 7 through door 5 and the gas burner 11 is lighted, the gas burning at full capacity. The bottom and side tiles 95 8 and 9 of the hearth increase in temperature very slowly but the products of combustion traveling up through the passages 12 and across the top plate 10 heat the top plate to a high temperature and this heat is transmitted to the interior of the hearth 7, giving 100 a rapid baking in the hearth.

If it is desired to bake hearth bread or the like the heating is continued until the bottom and sides of the hearth are raised to the 105 proper temperature. The bread is placed on the hearth 7 through the door 5 and the gas burner 11 is shut off. The heat which has been stored in the hearth is sufficient to give a slow, even baking. The retention of 110

heat within the oven is enhanced by the heat insulating walls of the oven proper.

The construction of the flue 13 with the inlet of the products of combustion at its front 5 14 gives a further advantage in overcoming any tendency toward cooling the front of the oven when opening the oven door for access to the hearth. The products of combustion, however, do not, at any time, reach the interior 10 of the hearth and come in contact with the material being baked.

My oven is readily adapted to use as a sectional baking plant. A plurality of units described may be readily stacked one upon 15 the other. Each oven having its own heater may be operated and controlled independently of any of the other sections. If it is desired, only one of the sections may be used and the operation of the other sections will 20 not be affected or interfered with. In this way, capacity can be increased at any time without discarding any equipment. Another advantage of a system of independent oven units is that one or more may be shut 25 down for repairs or cleaning without necessitating shutting down the entire plant, as is necessary when one large oven is used.

What I claim is:—

1. A bake oven comprising a heat insulated chamber, a heat-retaining hearth, a heat-conducting top for the hearth, a gas burner below the hearth, vertical passages 30 for products of combustion between the sides of the hearth and the side walls of the chamber extending throughout their length, means 35 extending from the rear wall of the chamber along the top of the hearth and terminating

adjacent the forward end thereof for conducting away the products of combustion, and a door in the front wall of the chamber. 40

2. A bake oven comprising a heat insulated chamber, a heat-retaining hearth, a heat-conducting top for the hearth, a gas burner below the hearth, vertical passages 45 for products of combustion between the sides of the hearth and the side walls of the chamber coextensive with the length thereof, a longitudinal flue extending across the top of the hearth, a chimney attached to the rear of the chamber, said flue being open at its front 50 end and being connected to the chimney at its rear end, and a door in the front wall of the chamber for access to the hearth.

3. A bake oven comprising a heat insulated chamber, an oven therein spaced from the sides of said chamber throughout its length but abutting the front and rear walls thereof, said oven comprising a heat-retaining hearth, a heat-conducting top for the hearth sealed thereto, said hearth and top 55 being spaced from the bottom and top, respectively, of said heat insulated chamber, and a flue extending forwardly from the rear of said heat insulated chamber and terminating adjacent the forward wall thereof above 60 said oven whereby the products of combustion passing upwardly between the side walls of the oven and chamber throughout their length will be drawn to the forward part of said chamber and thence will pass through 65 said flue to be conducted away.

In testimony whereof, I have hereunto affixed my signature.

RAYMOND MOWER CONNER.
